GARAGE DOOR HINGE

Henry P. Lipking, Fresno, Calif., assignor to
Harlan E. Stocks, Fresno, Calif.

Application July 31, 1952, Serial No. 301,881

6 Claims. (Cl. 16—129)

The present invention relates to hinge mountings and more particularly relates to a hinge mounting construction for overhead doors, such as those commonly used in garages, warehouses, airplane hangars, etc.

In the past, many types of hinge mountings for overhead doors have found commercial acceptance in the building industry. However, nearly all of these mountings include portions which must project some distance within the building on which the door is mounted thereby seriously affecting the full utilization of the garage or warehouse space. Further, the bulk of the prior art hinge mountings of this character require considerable clearance above the door header in order to permit the required vertical swinging movement of the door. Also, it has been noted in the prior art mountings of this character that due to a large variance in the tensioning of the spring as the door is vertically swung, an undesirable snap action results that will not permit the door to be held in selected positions.

Therefore, the objects of this invention are primarily to provide a hinge mounting that does not have any projecting lugs, arms, brackets or springs extending within the interior of the building, and to provide a hinge mounting for an overhead door whereby a very low overhead clearance is required in the operation of the door, the present invention requiring only five inches clearance in contrast to a minimum of nine inches in prior art devices of the same character.

It is also an object of the invention to provide a hinge mounting bracket for overhead doors which is spring actuated and whereby the spring is maintained in substantially the same state of tension at all times during the operation of the door between open and closed positions.

These, together with various ancillary objects and features of the invention which will later become apparent as the following description proceeds, are attained by this hinge mounting, a preferred embodiment of which is shown by way of example only in the accompanying drawings, wherein:

Figure 1 is a side elevational view of the overhead door hinge mounting with the door shown in open position;

Figure 2 is a side elevational view of the hinge mounting showing the door in closed position;

Figure 3 is a front elevational view taken from the inside of a building of the hinge mounting of the present invention;

Figure 4 is an end view of the hinge mounting taken substantially along section line 4—4 of Figure 1; and

Figure 5 is an exploded view of the elements comprising the hinge mounting.

Referring now to the accompanying drawings in detail wherein like reference numerals designate like parts throughout the various views, the hinge mounting is designated generally by the numeral 10 which, in the preferred embodiment shown in the drawings, interconnects a door jamb 12 and a door 14. It is to be noted that although only one door jamb and one hinge mounting are shown in the drawings, a similar jamb frames the

2

other side of the door 14 with the header 16 interconnecting these jambs and completing the door framing. Thus, the overhead door 14 swings about hinge mountings 10 mounted on each of the door jambs.

5 The hinge mounting 10 comprises a mounting bracket 18 which is in the form of an angle iron having flanges 20 and 22. Each of the flanges 20 and 22 has a portion thereof cut away in the interest of lightness and material saving. The cut-away portion in the flange 20 takes the 10 form of a rectangular cut-away 24 throughout the length of the upper portion of this flange. The cut-away portion in flange 22 takes the form of a rectangular notch 26 cut in the upper portion of the flange to provide a projecting lug or arm 28 at the upper end thereof.

Vertically spaced apertures 30 are formed in the flange 20 of the bracket 18 and bolts 32 passing through these openings secure the angle bracket 18 to the upper portion of the door jamb 12 in such a manner that the flange 22 extends into the building 34.

25 Secured to the door 14 adjacent and parallel to the jamb 12 is an elongated angle iron member 36 having flanges 38 and 40. Flange 38 is formed with vertically aligned apertures 42 through which bolts 44 extend to fasten the angle member 36 to the door 14. It will be noted that when the door 14 is in closed position as shown in Figures 2 and 3, the elongated angle member 36 has its upper end disposed adjacent the lower end of the angle bracket 18 with its lower end being disposed remote from the angle bracket 18.

30 Arranged in the lower portion of the flange 22 of the bracket 18 is a pair of vertically staggered apertures 46 and 48 while the arm or lug 28 is provided with a plurality of horizontally spaced apertures 50. The upper end of the flange 40 of the angle member 36 is provided with an aperture 52 while the longer end of the flange 40 is provided with a plurality of vertically spaced apertures 54. Intermediate the ends of the flange 40 is secured a lug 56 having a central aperture 58 therein.

35 Pivottally secured to the hinge bracket flange 22 via lower vertically staggered aperture 48 is a hinge arm or link 60. The lower end of the link 60 is pivotally secured to the lug 56 via aperture 58. In the upper vertically staggered aperture 46 of the flange 22 of the bracket 18 is pivotally secured one end of a second hinge arm or link 62, the lower end of which is secured via aperture 52 to the upper end of flange 40 of the angle member 36. As is obvious from the drawings, the upper link 62 is considerably shorter than the lower link 60 while the distance between their pivot points on the flange 22 is very short for a purpose that will become immediately apparent.

40 Secured in one of the selected apertures 50 of the lug 28 on the bracket 18 is a laterally extending bolt 64 having the head thereof in the form of an eyelet 66. 45 Hooked into the eyelet 66 is one end of a coil spring 68, the other end of which is hooked into a selected aperture 54 of the flange 40 by means of a bolt 70 similar in construction to bolt 64.

The link 60 is made into two parts 72 and 74, the 50 part 72 having a pair of longitudinally aligned slots 76 adjacent one end and the part 74 having a pair of longitudinally aligned apertures 78 at one end. The slots 76 are aligned with the apertures 78 and bolts 80 are passed therethrough to secure these two parts to one another. Thus, the link 62 is longitudinally adjustable to compensate for the desired positioning of the lug 56 on the flange 40. The plurality of apertures 50 and 54 to which the ends of the spring 68 are secured provide a convenient means whereby the tension of the spring 68 may be adjusted to compensate for doors of various weights.

55 It is to be further noted that the links 60 and 62 are

secured to the angle member 36 and the angle bracket 18 by means of rivets.

In operation, as the door 14 is lifted, it is pivoted about the hinge bracket 18 by virtue of the connection of the links 60 and 62 thereto. In view of the relatively close spacing of the pivotal connections of the hinge arms or links 60 and 62 to the flange 22 of the bracket 18, the door 14 is permitted to pivot about a substantially common pivot point whereby the clearance needed to vertically swing the door is held to an absolute minimum, namely, around five inches as stated in the objects of the invention, while also by virtue of this close pivotal connection of the links 60 and 62 to the flange 22, the spring 68 is maintained under an almost constant state of tension with very little variance, the variance acting only to decrease slightly as the door is raised to compensate for the change in position of the center of gravity of the door. Thus, any snap action which would ordinarily be present in hinge mountings of this type is prevented and the door may be stopped at any desired point during its raising and lowering motion. Further, it is obvious that by this arrangement, there is no necessity for elongated, lateral projections extending into the interior of the building upon which the door is mounted and, therefore, substantially all of the space within the building adjacent the garage door mounting is enabled to be utilized.

From the foregoing description, it is believed that the construction and operation of the hinge mounting will be readily apparent. However, since numerous modifications and changes will readily occur to those skilled in the art after a perusal of the foregoing specification taken in conjunction with the accompanying drawings, it is not desired to limit the invention to the exact construction shown and described. But, all suitable modifications and changes may be resorted to which fall within the scope of the appended claims.

Having described the invention, what is claimed as new is:

1. A hinge mounting for an overhead, swinging door comprising an angle bracket adapted to be mounted on a door jamb, an elongated angle member adapted to be mounted on a door, one end of said member being disposed adjacent said bracket and the other end of said member being disposed remote from said bracket, a pair of links pivoted at their ends to said bracket and member, the ends of said links pivoted to said bracket being longitudinally spaced from one another along the length of said bracket, the ends of said links pivoted to said member being spaced from one another along the length of the member, and a coil spring connected at its ends to said member and said bracket, said coil spring being secured to said bracket above said links and to said member below said links.

2. A hinge mounting for an overhead, swinging door comprising an angle bracket adapted to be mounted on a door jamb, an elongated angle member adapted to be mounted on a door, one end of said member being disposed adjacent said bracket and the other end of said member being disposed remote from said bracket, a pair of links pivoted at their ends to said bracket and member, the ends of said links pivoted to said bracket being longitudinally spaced from one another along the length of said bracket, the ends of said links pivoted to said member being spaced from one another along the length of the member, and a coil spring connected at its ends to said member and said bracket, said links being of different lengths, the shorter of said links being pivotally secured to the end of said member adjacent said bracket, said coil spring being secured to said bracket above said links and to said member below said links.

3. A hinge mounting for an overhead, swinging door comprising an angle bracket adapted to be mounted on

a door jamb, an elongated angle member adapted to be mounted on a door, one end of said member being disposed adjacent said bracket and the other end of said member being disposed remote from said bracket, a pair of links pivoted at their ends to said bracket and member, the ends of said links pivoted to said bracket being longitudinally spaced from one another along the length of said bracket and a coil spring connected at its ends to said member and said bracket, said links being of different lengths, the shorter of said links being pivotally secured to the end of said member adjacent said bracket, the longer of said links being pivotally secured to the member intermediate the ends of said member, the longer of said links being longitudinally adjustable, said coil spring being connected to said bracket above said links and to said member below the longer of said links.

4. A hinge mounting for an overhead, swinging door comprising an angle bracket adapted to be mounted on a door jamb, an elongated angle member adapted to be mounted on a door, one end of said member being disposed adjacent said bracket and the other end of said member being disposed remote from said bracket, a pair of links pivoted at their ends to said bracket and member, the ends of said links pivoted to said bracket being longitudinally spaced from one another along the length of said bracket, the ends of said links pivoted to said member being spaced from one another along the length of the member, and a coil spring connected at its ends to said member and said bracket, the remote end of said member having a plurality of longitudinally spaced apertures therein, one end of said spring being secured in a selected one of said apertures, said bracket having a plurality of transversely spaced apertures therein above said links, the other end of said spring being secured in one of said transversely spaced apertures, said links being of different lengths, the longer of said links being connected to the lower portion of said member and being of adjustable length.

5. A hinge mounting for an overhead, swinging door comprising a bracket adapted for mounting on a door jamb, fastening means adapted for vertical positioning on a door adjacent the door jamb to which the bracket is attached, a pair of links pivoted at their ends to said bracket and said fastening means, the ends of said links pivoted to said bracket being longitudinally spaced from one another along the length of the bracket, the ends of said links pivoted to said fastening means being vertically spaced from one another on said fastening means, and a coil spring connected at its ends to said fastening means and said bracket, said spring being attached to said bracket above said links, and to said fastening means below said links.

6. A hinge mounting for an overhead, swinging door comprising a bracket adapted for mounting on a door jamb, fastening means adapted for vertical positioning on a door adjacent the door jamb to which the bracket is attached, a pair of links pivoted at their ends to said bracket and said fastening means, the ends of said links pivoted to said bracket being longitudinally spaced from one another along the length of the bracket, the ends of said links pivoted to said fastening means being vertically spaced from one another on said fastening means, and a coil spring connected at its ends to said fastening means and said bracket, said spring being attached to said bracket above said links.
